UNITED STATES PATENT OFFICE

122,591

DESIGN FOR A CLOCKCASE

Ostilio Ciccarelli, Bristol, Conn., assignor to The
E. Ingraham Company, Bristol, Conn., a cor-
poration of Connecticut

Application June 11, 1940, Serial No. 92,924

Term of patent 14 years

To all whom it may concern:

Be it known that I, Ostilio Ciccarelli, a citizen of the United States, residing at Bristol, in the county of Hartford, State of Connecticut, have invented a new, original, and ornamental Design for a Clockcase, of which the following is a specification, reference being had to the accompanying drawing, forming a part thereof.

In the accompanying drawing:

Figure 1 is a perspective view of a clockcase showing my new design;

Fig. 2 is a side view thereof; and

Fig. 3 is a horizontal sectional view through the clockcase, being taken substantially on line 3—3 of Fig. 2.

The dominant characteristics of the applicant's design reside in a clock in which a portion of the face of the case lies in a vertical plane rearwardly of the plane of the remainder of the face of the case, whereby a portion of the bezel will lie forwardly of the face and a portion of the bezel rearwardly of the face. The design is further characterized in that the forwardmost face portion of the case has a convex curvature transversely of the case.

I claim:

The ornamental design for a clockcase, substantially as shown and described.

OSTILIO CICCARELLI.
